DESIGN FOR A CHAFING DISH

Daniel C. O'Connell, New York, N. Y., assignor to
Sterno, Inc., New York, N. Y., a corporation of
New York

Original design application January 16, 1946, Se-
rial No. 125,616. Divided and this application
July 5, 1947, Serial No. 140,100

Term of patent 14 years

(Cl. D44—15)

To all whom it may concern:

Be it known that I, Daniel C. O'Connell, a citizen of the United States, residing at 840 Grand Concourse, New York, New York, have invented a new, original, and ornamental Design for a Chafing Dish, of which the following is a specification, reference being had to the accompanying drawing, forming part thereof, in which:

Fig. 1 is a front perspective view of a chafing dish embodying my new design;

Fig. 2 is a rear elevation thereof; and

Fig. 3 is a top plan view thereof.

This application is a division of my co-pending design patent application Serial Number D. 125,616, filed January 16, 1946.

The dominant features of the design reside in the portions shown in full lines.

I claim:

The ornamental design for a chafing dish, as shown and described.

DANIEL C. O'CONNELL.
